FIG. 6.

INVENTOR:—
E. A. CAMPBELL,
BY *James L. Hopkins,*

ATTORNEY.

UNITED STATES PATENT OFFICE.

EDWARD A. CAMPBELL, OF ST. LOUIS, MISSOURI.

DISPLAY-SIGN FOR AUTOMOBILES.

1,227,746.

Specification of Letters Patent. Patented May 29, 1917.

Application filed December 20, 1915. Serial No. 67,861.

To all whom it may concern:

Be it known that I, EDWARD A. CAMPBELL, a citizen of the United States, residing at the city of St. Louis, State of Missouri, have 5 invented certain new and useful Improvements in Display-Signs for Automobiles, of which the following is a specification, reference being had therein to the accompanying drawing.

10 My invention relates to improvements in display signs for automobiles, and has for its object to provide a sign for automobiles, to be mounted about the upper portion of the rear wheels, being constructed to serve 15 as a combined fender and mud guard, and carrying translucent sign lettering, capable of illumination.

In the drawings—

Figure 1 is a side elevation of the rear 20 portion of an automobile showing the device of my invention in place.

Fig. 2 is a top plan view of the same.

Fig. 3 is a transverse vertical view of the 25 same in section, taken on the line 3—3 of Fig. 2.

Fig. 4 is a diagrammatic view of the wiring employed in illumination of the sign, illustrating the dry cell receptacle in section.

Fig. 5 is an enlarged sectional view illustrating the mounting of the translucent sign 30 members in relation to the illuminating means.

Fig. 6 is an elevation of the sign carrying 35 member.

Fig. 7 is an enlarged detail in section of the hinged mounting of the sign-carrying member.

Fig. 8 is an enlarged sectional detail of 40 the blind employed to conceal the display matter when desired.

In the drawings, the mud guard 10 is provided on its inner side with the shield 11, and is secured to the body 12 by means of the brace 13.

45 Beneath the guard 10, at its outer edge, the fender, or sign carrying member 14 is mounted by means of the hinge 15, so that said fender 14 may be thrown outwardly and upwardly into the position indicated by dotted lines in Fig. 7 when it is desired to get 50 access to the wheel 16.

The fender 14 is provided with horizontal apertures 17, on the rear side of which translucent strips or blocks 18 are mounted by 55 means of the angle strips 19; the strips or blocks 18 being so slidably and removably

mounted that new display matter can be substituted when desired.

The fender 14 is provided with perforations 20, to the end that the blind 21 may be 60 secured to the fender 14 by the bolts 22 when it is desired to conceal the sign matter.

The guard 10 is provided with inwardly 65 projecting bolts 23 which serve to normally hold the fender 14 in vertical position within said guard 10. Upon the rear face of the fender 14 I provide several series of electric lamps 24, for the illumination of the translucent blocks or strips 18, said lamps 24 being wired as indicated by the numeral 70 25, being energized from the cell 26, by means of the switch 27.

The cells 26 are contained in a receptacle 28 on the under side of the guard 10, said receptacle 28 being provided with the hinged 75 door 29 to give access to said cells 26.

The blocks or strips 18 may be made of translucent material with opaque lettering thereon, or said blocks or strips 18 may be 80 constructed of opaque material having letters or other advertising symbols perforated therethrough, so as to be visible only when illuminated by the lamps 24. By the described construction I am enabled to use 85 the space beneath the guard 10 and outside of the wheel 16 for display advertising, visible by day or night, and so mounted as to serve as a fender 14 for the prevention of accidental injury to the wheel 16, or to persons 90 animals or other objects which might otherwise come in contact with the wheel 16; while said fender 14 is so mounted as to have no projection beyond the vertical plane of the outer edge of the guard 10.

Having thus described my invention, what 95 I claim as new, and desire to have secured to me by the grant of Letters Patent, is—

1. In a display sign for automobiles the combination of a mud-guard, a fender conforming to the contour thereof and movably mounted beneath said guard and having 100 a translucent sign portion, and means for illuminating said translucent sign.

2. In a display sign for automobiles the combination of a mud-guard, a fender conforming to the contour thereof and provided with a translucent sign portion and hingedly mounted beneath said mud-guard, so 105 that it may be swung outwardly therefrom, and means for illuminating said translucent sign.

3. In a display sign for automobiles, the

combination with a mud-guard thereof, of a sign carrying member conforming to the contour of said mud-guard, means for hingedly securing said member to the under side 5 of said mud-guard, whereby access may be had to the wheel of the vehicle by swinging said member outwardly, and means for securing said member against movement.

4. In a display sign for automobiles the 10 combination with a mud-guard thereof, of a sign carrying member conforming to the contour of said mud-guard and fitting therewithin, said member being provided with a flange, means secured to said flange and to 15 said mud-guard to permit a swinging movement of said member, and means for securing said member against swinging movement.

5. In a display sign for automobiles, the 20 combination with a mud-guard thereof, of a sign carrying member conforming to the contour of said mud-guard and provided with a translucent portion, means for hingedly securing said member to the under side

of said mud-guard whereby access may be 25 had to the wheel of the vehicle by swinging said member outwardly, display matter carried by said translucent portion, and illuminating means mounted behind said translucent portion.

6. In a display sign for automobiles, the 30 combination with a mud-guard thereof, of a sign carrying member conforming to the contour of said mud-guard, means for movably securing said member to the under side 35 of said mud-guard whereby access may be had to the wheel of the vehicle by swinging said member outwardly, means for securing said member against movement upon its hinge, a translucent sign carried by said 40 member, illuminating means mounted behind said translucent sign, and a blind removably mounted upon said member and covering said illuminating means.

In testimony whereof I hereunto affix my 45 signature.

EDWARD A. CAMPBELL.
